UNITED STATES PATENT OFFICE.

CHARLES R. BUFFINGTON, OF FORT BENTON, MONTANA.

CURRENT-MOTOR.

No. 823,665.

Specification of Letters Patent.

Patented June 19, 1906.

Application filed July 18, 1905. Serial No. 269,515.

To all whom it may concern:

Be it known that I, CHARLES R. BUFFINGTON, a citizen of the United States, residing at Fort Benton, in the county of Chouteau and State of Montana, have invented a new and useful Current-Motor, of which the following is a specification.

This invention relates to that class of hydraulic motors which are known as "current-motors" and which are principally utilized in comparatively shallow streams and rivers.

The present invention relates to that particular class of current-motors in which suitably-supported endless chains are provided with blades or paddles which are successively exposed to the action of the current, the power thus derived being transmitted from one of the chain-supporting shafts to the machinery or apparatus which is to be driven and which in the present instance consists of a water-elevating device.

The object of the invention is to simplify and improve the construction and operation of this class of devices; and with these and other ends in view, which will readily appear as the nature of the invention is better understood, the same consists in the improved construction and novel arrangement and combination of parts, which will be herein-after fully described, and particularly pointed out in the claims.

In the accompanying drawings has been illustrated a simple and preferred form of embodiment of the invention, it being, however, understood that no limitation is necessarily made to the precise structural details therein exhibited; but that the right is reserved to any changes, alterations, and modifications to which recourse may be had within the scope of the invention and without departing from the spirit or sacrificing the efficiency of the same.

In said drawings, Figure 1 is a top plan view of a hydraulic motor constructed in accordance with the principles of the invention; Fig. 2 is a side elevation of the same. Fig. 3 is an end view. Fig. 4 is a sectional detail view taken on the plane indicated by the line 4-4 in Fig. 1.

Corresponding parts in the several figures are indicated throughout by similar characters of reference.

The motor proper is supported by and be-

tween a pair of floats 1 and 2, both of which are provided with sloping ends 3-3 to concentrate the current between said floats. The latter are securely connected by means of cross beams or braces 4-4 and vertical bolts 5 or other suitable connecting means. The inner float 1, which is the one that in practice is nearest the shore, is wider than the outer float and of greater capacity, thus making it more buoyant to enable it to support the machinery to be driven, as will be hereinafter described. Said inner float is to be anchored to the shore in position for operation by means of braces, cables, anchors, and the like; but these may be of any well-known and approved construction and have not been indicated in the drawings, with the exception of portions of braces 6. (Shown in Fig. 1.)

The motor proper is provided with a frame including longitudinal beams 7, transverse beams 8, and diagonal brace-beams 9; but the structural details of said frame may be modified within the scope of the invention. Said frame or "carriage," as it is preferably called, is provided at the ends thereof with bearings 10 for shafts 11, carrying sprocket-wheels 12, supporting a pair of endless chains 13, which are so disposed as to pass entirely around the carriage from end to end of the latter. Hingedly connected with said chains are blades or paddles 14, at the outer edges of which are attached brace-chains 15, the free ends of which are connected with the endless chains 13 by means such as snap-hooks 16, whereby said brace-chains may be shifted from one side of said blades to the other; the adjustment of the brace-chains being such as to permit the blades to swing to an angle of approximately ninety degrees to the lower leads of the chains 13. It is important that the brace-chains or stay-chains shall be capable of being shifted from one side to the other in order that the movement may be reversed when the device is removed from one bank of a stream to the opposite bank.

Cross-bars 8 of the motor-carriage are provided at the ends thereof with annularly-grooved wheels or rollers 18, traveling in curved grooves 19, formed between uprights 20 21, which are secured to and supported by the inner sides of the floats. The grooves 19 are faced with track irons or rails 22, having

ribs 23, engaging the annular grooves in the wheels or rollers, which are thereby retained in engagement with the guide-slots. Frames 24, supported upon the floats, are provided 5 with bearings 25 for windlass-shafts 26, upon which are wound chains 27, the free ends of which are connected with the cross-pieces 8, near the ends of the latter, in such a position as not to interfere with the movement of the 10 blades or paddles. The shafts 26 have cranks 28, whereby they may be rotated, and they are equipped with ratchet-teeth 29, engaged by locking-pawl 30, whereby they may be retained against backward rotation. 15 It will be seen that by rotating these windlass-shafts the motor-carriage may be raised or lowered and that it may be supported above the water-level, if desired.

Upon the inner float 1 is erected a suitable 20 scaffolding or tower structure 31, near the upper and lower ends of which are bearings for transverse shafts 32 and 33, each carrying a pair of sprocket-wheels 34, over which pass a pair of endless chains 35, between which buckets 36 are suitably mounted, thus constituting a water-elevator. The lower shaft 33 carries an additional sprocket-wheel 37, which is connected by a chain 38 with a sprocket-wheel 39 upon one of the motor-shafts 11, from which motion is thus transmitted to the water-elevating device. The buckets of the latter are made to discharge into a trough or flume 40, one end of which is supported, as upon a bracket 41, at the upper end of the scaffolding or structure 31.

The lower cross-braces 4, whereby the floats are connected with each other, are preferably beveled upon their outer sides, as shown at 42 in Fig. 3 of the drawings, for the purpose 40 of offering the least possible resistance to the incoming current.

As has been already stated, the grooves 19, in which the guide-wheels 18 of the motor-carriage are made to travel, are curved or 45 arcuate. This is in order that the chain 38, connecting the sprocket 39 of the motor-shaft 11 with the sprocket 37 upon the driven shaft 33, may be preserved in a taut condition at any degree of vertical adjustment of 50 the motor-carriage, and the said guide-grooves will be curved accordingly.

From the foregoing description, taken in connection with the drawings hereto annexed, the operation and advantages of this 55 invention will be readily understood. The device is anchored in position for operation as near the shore of a stream as may be convenient. When the motor-carriage is lowered, the current entering between the floats 60 will operate against the exposed faces of such of the blades or paddles as are connected with the lower leads of the chains 13, which latter are thereby set in motion, it being understood that the lower edges of the blades which 65 are in action are to be connected with the sup-

porting-chains at points in front of said blades. When the blades reach the rear end of the carriage, they will fold down flat upon the latter and will remain in this position while traversing the upper lead. At the 70 front end of the carriage the blades, when their centers of gravity pass beyond the sprocket-wheels 12, will drop in an outward direction until checked by the stay-chains 15, thus presenting their faces to the incoming 75 current. The operation continues until the motor-carriage is elevated above the influence of the current. When the device is shifted from one bank to the opposite bank, the stay-chains 15 are shifted to the opposite 80 sides of the blades or paddles in order that the motion may be reversed, as will be readily understood. It will also then be necessary to reverse the position of the buckets upon the water-elevator; but these changes may be 85 easily accomplished and are not frequently called for.

Having thus described the invention, what is claimed is—

1. In a current-motor, a pair of floats 90 spaced and connected to form a sluiceway, pairs of guides supported upon said floats opposite to each other and having correspondingly-curved arcuate grooves, a rectangular frame or carriage having cross-bars provided with rollers guided in said grooves, frames supported upon the floats adjacent to the guides, a pair of shafts or drums journaled upon said frames and extending transversely across the sluiceway, flexible members connecting said drums with the cross-bars of the frame or carriage, means for operating the drums to effect vertical adjustment of the frame or carriage, shafts journaled in the frame or carriage, sprocket-wheels upon said 95 shafts, paddle-carrying chains guided over said sprocket-wheels, a shaft supported for rotation concentric with the arcuate grooves in one pair of guides, and means for transmitting motion to said shaft from one of the motor-shafts journaled in the frame or carriage. 100
2. In a current-motor, a pair of floats spaced and connected to form a sluiceway, pairs of guides supported upon said floats opposite to each other and having correspondingly-curved arcuate grooves, ribbed rails secured upon the faces of said grooves, a rectangular frame or carriage having cross-bars provided with annularly-grooved rollers guided in the arcuate grooves and engaging 110 the ribbed rails with which said grooves are faced, frames supported upon the floats adjacent to the guides, a pair of shafts or drums journaled upon said frames and extending transversely across the sluiceway, flexible members connecting said drums with the cross-bars of the frame or carriage, means for operating the drums to effect vertical adjustment of the frame or carriage in the arc of a circle, motor-shafts journaled in the carriage, 115 120 125 130

endless chains guided over said shafts and carrying blades or paddles, a shaft supported for rotation concentric with the arcuate grooves in one pair of guides, and means for transmitting motion to said shaft from one of the motor-shafts upon the carriage.

5 In testimony that I claim the foregoing as

my own I have hereto affixed my signature in the presence of two witnesses.

CHAS. R. BUFFINGTON.
